UNITED STATES PATENT OFFICE.

SAM P. WHITWORTH, OF MERKEL, TEXAS.

HEADER.

1,015,368.

Specification of Letters Patent. Patented Jan. 23, 1912.

Application filed June 16, 1909. Serial No. 502,552.

To all whom it may concern:

Be it known that I, SAM P. WHITWORTH, citizen of the United States, residing at Merkel, in the county of Taylor and State of Texas, have invented certain new and useful Improvements in Headers, of which the following is a specification.

This invention comprehends certain new and useful improvements in grain headers, and the primary object of the invention is a machine of this character which is composed of comparatively few and simple parts that may be cheaply manufactured and easily assembled and which will operate efficiently to head the grain and carry the heads rearwardly into a trough or receptacle suspended within the framework of the implement, the present embodiment of the invention being arranged to head two rows at the same time.

With these and other objects in view as will more fully appear as the description proceeds, the invention consists in certain constructions, arrangements and combinations of the parts that I shall hereinafter fully describe and claim.

For a full understanding of the invention, reference is to be had to the following description and accompanying drawings, in which:

Figure 1 is a perspective view of my improved header, one of the chutes being omitted, to show parts which it would otherwise hide; Fig. 2 is a longitudinal sectional view, one of the chutes being indicated in dotted lines; Fig. 3 is a top plan view; Fig. 4 is a detail top plan view, partly in section, of the means for actuating the knife blades; Fig. 5 is a detail view of one of the guards, and Fig. 6 is a detail view of one of the reels.

Corresponding and like parts are referred to in the following description and indicated in all the views of the drawings by the same reference characters.

The main framework of my improved header comprises inner and outer longitudinal sills 1 and 2, and front and rear cross bars 3 and 4, the rear cross bar being extended at one end, as indicated at 4^a, to form the rear end of a side frame, said side frame also including a longitudinal sill 5 and a front cross bar 6. The main driving and ground wheel 7 is mounted in the said side frame between the sills 1 and 5 and is arranged to impart movement to a sprocket

wheel 8. A chain 9 passes over the sprocket wheel 8 and over a corresponding, but preferably smaller wheel 10 on one end of a transversely extending shaft 11 journaled in the framework, as shown. Preferably, the sprocket wheel 10 is loose on the shaft 11 and is arranged to be connected thereto and released therefrom by any suitable clutch mechanism, the shipper lever of which is arranged in proper proximity to the driver's seat 12, the seat spring of which is secured to the intermediate longitudinal sill 1 of the framework.

13 designates a bracket which is secured to and which depends from the outside sill 2 of the framework and is provided at its lower outwardly projecting end with a spindle on which the grain wheel or ground wheel 14 is journaled.

The countershaft 11 has a sprocket wheel 15 secured to it, and over this sprocket wheel there passes a chain 16, the runs of which extend forwardly and over a sprocket wheel 17 on a transversely extending shaft 18 which is the actuating shaft for the header mechanism. This shaft 18 is journaled at its ends in bearings secured to the longitudinal bars 19 of an auxiliary frame which constitutes the support for the heading mechanism. This frame comprises, in addition to the longitudinal bars 19, the front and rear standards 20 which are arranged for vertical movement in the bracket straps 21 that are secured to the inner faces of the side sills 1 and 2. In order to elevate or lower the heading mechanism by the vertical adjustment of this auxiliary frame, links 22 are connected to the side bars 19 and are also connected to cranks 23 which extend perpendicularly from a transversely extending rod 24 journaled to partly rotate about its longitudinal axis in the side sills 1 and 2. A hand lever 25 is connected to one end of the rod 24 and its detent is arranged for locking engagement with a segment 26 secured to one side of the sill 1.

A finger bar 27 with two sets of forwardly extending and diverting fingers 28, is secured in any desired way upon the longitudinal bars 19 of the elevated auxiliary framework, and a knife bar 29 reciprocates in a transverse direction upon said finger bar and carries at its ends the header blades 30. The knife bar 29 is reciprocated by means of a pitman 31 which is connected at its outer end to a crank disk 32 secured on

a relatively short shaft 33. The shaft 33 carries a relatively small beveled pinion 34 meshing with a bevel gear wheel 35 on the end of the shaft 18, the two pinions 34 and 35 being preferably located in a casing 36 secured to the inner side of one of the bars 19.

Brackets 37 are secured upon the finger bar 27 at the ends thereof, and a reel shaft 10 38 is journaled in said brackets and carries two reels 39 at its ends. The shaft 38 is rotated through the instrumentality of a sprocket wheel 40 secured thereto at its middle and a sprocket chain 41 passing around 15 the sprocket wheel 40 and around a corresponding wheel 42 on the shaft 18. Guards co-act with the fingers 28 of the finger bar and with the reels 39, to properly pass the grain to the knives 30 at the proper elevation. In 20 the present arrangement of the invention, these guard devices include transversely extending rollers 43 journaled in uprights 44 that are arranged for a vertical adjustment, as shown, in collars 45 mounted upon forwardly diverging guard rods 46. There is 25 a pair of guard rods provided in front of each cutting device. The inner or adjacent guard rods meet in a point and constitute a wedge which enters between the stalks to 30 divide the same into two rows and to direct said rows to the respective cutters.

As the heads are cut, they pass from the cutting mechanism onto rearwardly sloping chutes 47 and are conveyed thereby rearwardly and downwardly into a trough or receptacle 48 which is secured to and suspended within the main portion of the supporting framework between the sills 1 and 2 and front and rear cross bars 3 and 4. The 35 trough 48 is provided at its rear end with a discharge door 49 hinged from its upper edge, as shown, the hinge rod 50 of said door being provided with a rearwardly and upwardly projecting crank 51 which is secured to the rear end of a link rod 52, said 40 link rod being in turn connected at the forward end to a foot lever 53 fulcrumed on the longitudinal sill 1 in proximity to the driver's seat 12. By this means it is evident 45 the driver may easily swing the door 49 rearwardly and upwardly to discharge the load whenever desired. In order to insure

the proper closing of the door 49 and to hold it in closed position, said door has springs 54 connected to its side edges, said springs 55 being also connected to slotted straps 55 adjustably secured by set screws to the sides of the trough 48, the adjustment of these straps varying the tension upon the door closing springs.

From the foregoing description in connection with the accompanying drawings, it is believed that the operation of my improved header will be obvious.

In the practical use of the machine, after 60 the supporting frame for the header mechanism has been vertically adjusted to the desired elevation, the clutch for the sprocket wheel 10 is thrown in and the machine caused to travel across the field, the grain 70 being divided by guards 46 into two rows and passed underneath the guard rollers 43 and by the reels 39 to the knives 30. As the grain is cut, the heads pass rearwardly to the chutes 47 and are thereby conveyed 75 downwardly and rearwardly into the trough 48, from whence they are discharged from time to time by the driver or operator pressing his foot upon the foot treadle or lever 53 so as to open the spring closed door 49. 80

Having thus described the invention, what is claimed as new is:

A header comprising a frame, a traction wheel partially supporting the same, a receptacle fixed to the frame and having a 85 downwardly and rearwardly inclined forward side, a supplemental frame adjustably mounted upon the first mentioned frame, means for adjusting the supplemental frame vertically with relation to the first mentioned frame, a cutting apparatus mounted upon the supplemental frame, means for operating the cutting apparatus from the traction wheel, and a chute mounted upon the supplemental frame behind the cutting apparatus and having its delivery end disposed over the inclined side of the receptacle.

In testimony whereof I affix my signature in presence two witnesses.

SAM P. WHITWORTH. [L. S.]
